[57] CLAIM

The ornamental design for a bidet, as shown and described.

DESCRIPTION

FIG. 1 is a bottom perspective view of a bidet showing our new design;

FIG. 2 is another bottom perspective view showing a second embodiment thereof;

FIG. 3 is a third bottom perspective view showing a third embodiment thereof;

FIG. 4 is a side elevational view of the body thereof, the opposite side being a mirror image of the side shown;

FIG. 5 is a top plan view of FIG. 4;

FIG. 6 is a bottom plan view of FIG. 4;

FIG. 7 is a bottom plan view of the nozzle shown in FIG. 1;

FIG. 8 is a top plan view of FIG. 7;

FIG. 9 is a side elevational view of FIG. 7, the opposite side being a mirror image of the side shown;

FIG. 10 is a bottom plan view of the nozzle shown in FIG. 2;

FIG. 11 is a top plan view of FIG. 10;

FIG. 12 is a side elevational view of FIG. 10, the opposite side being a mirror image of the side shown;

FIG. 13 is a bottom plan view of the nozzle shown in FIG. 3;

FIG. 14 is a top plan view of FIG. 13; and,

FIG. 15 is a side elevational view of FIG. 13, the opposite side being a mirror image of the side shown.

It is to be understood that the connecting hose has been broken away in FIGS. 4, 5 and 6 for convenience of illustration.
